DESIGN FOR A COAT

Jack Cohen, New York, N. Y.

Application December 21, 1939, Serial No. 89,059

Term of patent 3½ years

To all whom it may concern:

Be it known that I, Jack Cohen, a citizen of the United States of America, residing in the city of New York, county of New York, and State of New York, have invented a new, original, and ornamental Design for a Coat, of which the following is a specification, reference being had to the accompanying drawing, forming part thereof.

Fig. 1 is a front view of a coat showing my new design.

Fig. 2 is a rear view thereof.

Fig. 3 is a front view of the detachable cape portion of the coat shown in Figure 1.

Fig. 4 is a fragmentary view of the rear portion of coat showing the rear cape portion in closed position. The characteristic feature of my design resides in the combination on the specific coat disclosed of the specific detachable cape as shown.

I claim:

The ornamental design for a coat, substantially as shown and described.

JACK COHEN.
